UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

CAR TRUCK.

Application filed June 3, 1925. Serial No. 34,706.

My invention relates to railway rolling stock and consists in an improved truck of the general type illustrated in Patent No. 1,279,425 issued to me September 17, 1918, in which there is a combination of load supporting springs and compensating springs, the compensating springs normally being inactive but functioning upon momentary removal of the load of the car body from the 10 load supporting springs.

One object of my present invention is to provide a frame for this type of truck in which the familiar truss design of said frame is retained but is modified to accommodate the compensating springs of the particular type of truck referred to.

Another object of my invention is to provide against the accumulation of dirt or other foreign matter in bearing surfaces or other places where accumulation would be likely to interfere with the operation of the truck.

Another object of my invention is to provide against displacement of any of the springs and, in the event of breakage of one 25 of the main load supporting springs, to provide against undesirable lowering of the body supporting portion of the truck.

Another object of my invention is to reduce the width of the side frame and spring 30 structure, thereby providing greater clearance for the truck wheels and providing a low eccentric movement in the top rail about a longitudinal plane.

Additional minor objects of my invention 35 will be obvious from the description of the detailed construction of the invention.

In the accompanying drawings which illustrate a preferred embodiment of my invention—

40 Figure 1 is a top view and in part a horizontal section through one longitudinal half of my improved truck.

Figure 2 is in part a side elevation and in part a vertical longitudinal section on 45 the longitudinal center line of the truck side frame.

Figure 3 is a transverse vertical section on line 3—3 of Figure 2.

Figure 4 is a transverse vertical section 50 through the journal box and adjacent portion of the truck frame.

The truck has the usual axles 1 and wheels 2, the axle journals 3 carrying journal boxes 4 which may be of usual construction except that the tops of these journal boxes are 55

each provided with a cylindrical elevation or boss 5 which forms a swivel bearing for the truck side frame.

The side frame is shown as a one-piece casting and between the journal boxes includes a top chord 7 and a depressed bottom chord 8. These chords are united over the journal boxes in a portion 9 having a box-shape cross section and provided with depending portions 10 which slidably engage the sides of the journal box. The portion 9 is also provided with a circular seat 11 which rests upon the journal box boss 5. Seat 11 has a depending flange 12 which overhangs the bearing on the journal box 70 and guards against the admission of cinders and dirt to the bearing surfaces of the box and frame. Cooperating projection 13 on the journal box and corresponding recess 14 in the frame center the frame and box 75 bearing and also receive the bolt 15 by which the frame and box are held in assembled position.

The lower chord 8 of the frame is provided with a seat 16 for the load supporting 80 springs 17. Suitable upstanding lugs 18 on spring seat 16 prevent the lateral displacement of the load springs.

Springs 17 carry a cap 19 which forms a seat for the compensating springs 20 and 85 positions these springs by centering lugs 6. These compensating springs carry a cage 21, the upper portion of which has an upwardly convex bearing for the upper center bearing 22 which supports the car mounted upon the 90 truck. Member 22 is provided with depending flanges 23 which guard against the entrance of dirt or other foreign matter to the bearing surface.

It will be noted that the top chord 7 of the 95 truck frame is provided with a vertical opening at its center to permit the passage therethrough of spring cage 21 and the enclosed springs. At the ends of this opening the chord has transverse walls 24 which extend slightly beyond the sides of the chord and are flanged as indicated to form a channel-shape which receives and guides the adjacent portion of the spring cage 21.

The central portion of spring cage 21 includes a cylindrical structure 26, the lower end of which contacts with cap 19 before compensating springs 20 are fully compressed. This is the normal relation of the spring cage compensating springs and cap 110

- 19 and the load is therefore normally carried on the load springs 17 irrespective of springs 20. The ends of cage 21 extend downwardly inside the vertical walls 24 of the frame and 5 form guides for the load springs 17 and for the spring cap 19. To avoid pockets for dirt at the lower ends of the channels formed by walls 24, the flanges on these walls are cut away as indicated at 27 in Figure 2.
- 10 The top chord 7 of the frame has a lateral projection 28 provided with spaced vertical ears 29 which provide bearings for a brake hanger pin 30. Flanges 31 on one of the ears 29 provide for the mounting of a cotter 15 32 which extends past the head of pin 30 and prevents its accidental removal. This arrangement eliminates the necessity of extending the other end of the pin and the provision of a cotter therethrough and 20 greatly facilitates the application and removal of the pin and the brake hanger for repair or other purposes.

In Figure 2 I illustrate a single load spring and two separate compensating springs. It is to be understood that each of 25 these springs preferably includes a set of two or three springs as indicated in Figures 1 and 3 and as is customary in car truck construction, the showing of the complete set in each figure being eliminated to avoid 30 confusion.

Tie bars 33 and portions of the brake rigging are shown in the position which they occupy when assembled with the truck but 35 form no part of my present invention.

It is to be noted that the top of cage 21 extends laterally over the top chord 7 of the truck frame and in the event of breakage or removal of one or more of the load carrying 40 springs 17, the downward movement of cage 21 and its load will be limited by the engagement of the laterally extending portion of cage 21 with the top of the side frame, thus avoiding undue lowering of one point of 45 support for the load.

Obviously, the details of my invention may be varied without departing from the spirit thereof and I contemplate such modifications as are included in the scope of the 50 following claims.

I claim:

1. In a car truck, a frame including a horizontal top chord and a depressed bottom chord, spaced posts between said chords providing a lateral opening between them, said top chord having a vertical opening for springs carried by said bottom chord.
2. In a car truck, a frame including a top and a bottom chord, said top chord being 60 box-shape in cross section and having a vertical opening for springs carried by said bottom chord.
3. In a car truck, a frame including a top and a bottom chord, said top chord having a 65 vertical opening, a spring cage slidable

through said opening, and springs retained by said cage and movable therewith through said opening.

4. In a car truck, a side frame including top and bottom chords, said top chord being 70 box-shape in cross section and increasing in width from its ends toward its middle, a vertical opening in the middle portion of said chord, and transverse walls across the ends of said opening.

5. In a car truck, a side frame including top and bottom chords, said top chord being 75 box-shape in cross section and increasing in width from its ends toward its middle, a vertical opening in the middle portion of 80 said chord, transverse walls across the ends of said opening, and a spring cage supported on said bottom chord and slidable through said opening in the top chord.

6. In a car truck, a side frame including 85 top and bottom chords, said top chord being box-shape in cross section and comprising a middle portion with parallel sides and adjacent portions with converging sides, there being a vertical opening through said middle 90 portion, and vertical transverse walls connecting said sides at the angles between their parallel and converging portions.

7. In a car truck, a truck side frame, truck load supporting springs mounted on said frame, and compensating springs having 95 their axes spaced longitudinally of the truck and located between said load springs and the truck load.

8. In a car truck, a truck side frame, a 100 group of truck load supporting springs mounted on said frame, and compensating springs aligned longitudinally of the truck and located substantially above said group of load springs.

9. In a car truck, a truck side frame provided with a spring seat extending laterally of the remainder of said frame, and load supporting springs mounted on said seat and projecting laterally beyond said frame, and compensating springs carried by said load springs and located between the planes of the sides of said frame.

10. In a car truck, a truck side frame 110 provided with a spring seat, load springs on said seat with their axes spaced transversely of said frame, and compensating springs carried by said load springs with their axes between the planes of the axes of said load springs.

11. In a car truck, a truck side frame having a top and a bottom chord, a vertical opening in said top chord, load springs seated on said bottom chord and projecting laterally beyond the vertical planes of the sides of said top chord, and compensating springs carried on said load springs and extending through said opening.

12. In a car truck, a frame with top and bottom chords, said top chord being box- 120

- shape in cross section and provided with openings in its top and bottom walls intermediate its ends, transverse vertical walls at the ends of said openings, and a spring cage 65
55 slidable between said transverse walls and through said openings.
13. In a car truck, a frame with top and bottom chords, said top chord being provided with a vertical opening in its top and bottom walls intermediate its ends, transverse vertical walls at the ends of said openings, each having a vertical flange extending inwardly of said openings, and a spring cage 70
105 slidable through said openings and guided by said flanges.
14. In a car truck, a frame with top and bottom chords, said top chord being provided with openings in its top and bottom walls intermediate its ends, channel-shape 75
20 vertical walls at the ends of said opening facing each other, and a spring cage slidable through said openings and retained and guided by said channel-shaped walls.
15. In a car truck, a frame including a 80
25 top and a bottom chord, said top chord having a vertical opening, a spring cage in said opening, springs supporting said cage, a convex top on said cage, and a load carrying member having a concave lower face 85
30 mounted on said cage top.
16. In a car truck, a frame including a top and a bottom chord, said top chord having a vertical opening, a spring cage in 90
35 said opening, springs supporting said cage, a top on said cage, and a load carrying member mounted on said cage top with a depending flange extending below the edge 95
40 of said top to exclude foreign matter from between said top and member.
17. In a car truck, a frame including a top chord and a bottom chord, springs on 100
45 said lower chord, a spring cap carried by said springs, secondary springs on said cap, a cage carried by said cap and secondary springs and movable through said top chord, and a downward extension on said cage 105
50 adapted to guide said first-mentioned springs.
18. In a car truck, a side frame casting having an integral top and an integral bottom chord, a portion of said bottom chord forming a spring seat, there being an integral lug on the edge of said spring seat for holding a plurality of spaced springs, mounted on said seat, against transverse 110
55 movement off of said seat.
19. In a car truck, a frame including a spring seat and vertical walls adjacent said seat, a spring cage slidable vertically in said frame and guided by said wall, downward 115
60 projections on said cage adjacent said walls, and inclined surfaces between said walls and spring seat to avoid accumulation of dirt on said spring seat beneath said projections.
20. In a car truck, a frame including a spring seat and vertical channel-shape walls adjacent said seat, a spring cage slidable vertically in said frame and extending into the channels of said walls and guided thereby, the flanges of said walls being cut away 120
65 adjacent said spring seat to avoid pockets for dirt at the lower ends of said walls.
21. In a car truck of the class described, a side frame including a top chord, an opening in said top chord for compensating springs, a load bearing normally supported by said springs above said top chord, and interengaging surfaces on said top chord and load bearing for limiting downward movement 75
70 of the latter.
22. In a car truck of the class described, a side frame with an upper and a lower chord, load springs carried on said lower chord, compensating springs carried on said load springs, a cage for said compensating 80
85 springs, and cooperating elements on said cage and top chord for limiting downward movement of said cage.
23. In a truck of the class described, a side frame, load springs mounted thereon, 90
95 compensating springs carried on said load springs, a load bearing carried by said compensating springs, and members on said frame and bearing for supporting the latter directly on said frame in the event of the failure or removal of said load springs.
24. In a car truck, wheels, axles, journal boxes on said axles, an elevated boss on the top of each of said bosses forming a bearing for the side frame, and a depending 100
105 shoulder on said side frame surrounding said boss to exclude dirt from the bearing surfaces.
25. In a truck of the class described, a load spring, a cap carried thereby, a compensating spring seated on said cap and centered thereby, and a spring cage carried by said compensating spring and forming a guide for said cap.
26. In a truck of the class described, a side frame including a spring seat and vertical walls adjacent said seat, load springs mounted on said seat, a cap on said springs, compensating springs carried on said cap, a cage carried by said compensating springs 110
115 and guided by said walls and extending downwardly between said cap and said walls to form a guide for said cap.
27. In a car truck, a side frame having a lateral projection, spaced ears on said projection forming bearings for a brake hanger pin, flanges on one of said ears for mounting a removable cotter pin behind the head of said pin to retain said pin in position.
- In testimony whereof I hereunto affix my 120
125 signature this 28th day of May, 1925.

H. M. PFLAGER.
